(57) **CLAIM**

The ornamental design for a set of end shrouds for stacked conveyor tunnel oven, as shown and described.

DESCRIPTION

FIG. 1 is a front, right side perspective view of a set of end shrouds for stacked conveyor tunnel oven showing the new design.

FIG. 2 is a front, left side perspective view thereof.

FIG. 3 is a rear view thereof; and,

FIG. 4 is a bottom view thereof.

The broken lines in the drawings depict environment and form no part of the claimed design.
